[57] CLAIM

The ornamental design for a display stand, as shown and described.

DESCRIPTION

FIG. 1 is an end elevational view of a display stand showing my new design, the end opposite being identical;

FIG. 2 is a front elevational view thereof;

FIG. 3 is a top plan view thereof;

FIG. 4 is a bottom view thereof; and

FIG. 5 is a sectional view in the direction of the arrows on line 5—5 of FIG. 2.
